DESIGN FOR A SERVING TONG

Pete Moniodis, Canonsburg, Pa.

Application September 24, 1940, Serial No. 95,332

Term of patent 14 years

To all whom it may concern:

Be it known that I, Pete Moniodis, a citizen of the United States of America, residing at Canonsburg, in the county of Washington and State of Pennsylvania, have invented a new, original, and ornamental Design for Serving Tongs, of which the following is a specification, reference being had to the accompanying drawing, forming part thereof.

Fig. 1 is a side elevational view of the serving-tong, showing my new design;

Fig. 2 is a front elevational view of the fork side of the serving-tong; and

Fig. 3 is a front elevational view of the spoon side of the serving-tong.

I claim:

The ornamental design for a serving tong, as shown.

PETE MONIODIS.
